UNITED STATES PATENT OFFICE.

JOSEPH E. LOMAS, OF SMUGGLER, COLORADO.

LIFE-PRESERVER.

1,162,087.

Specification of Letters Patent. Patented Nov. 30, 1915.

Application filed September 18, 1914. Serial No. 862,362.

To all whom it may concern:

Be it known that I, JOSEPH E. LOMAS, a citizen of the United States, residing at Smuggler, in the county of San Miguel and 5 State of Colorado, have invented certain new and useful Improvements in Life-Preservers, of which the following is a specification.

My invention relates to new and useful 10 improvements in a life preserver.

The primary object of the invention is the provision of such a preserver which will entirely inclose the body.

A further object of the invention is the 15 provision of a preserver which may be easily attached and detached.

A still further object of the invention is a preserver having means secured thereto for keeping the body in a vertical position.

20 With these and other objects in view the invention consists in the novel details of construction and arrangement of parts which will be more clearly understood from the following description and drawings, in which,

25 Figure 1 is a front elevation parts broken away. Fig. 2 is a detail of the head section, and Fig. 3 is a fragmental vertical section through the joint for the head and body section.

30 In the drawings, the letter A represents the body portion of the preserver and B the head portion, both of which are constructed of rubber or other suitable water proof material. The body portion A is formed with 35 the legs 1, the feet 2 and arms 3 having the fingers 4 at the end thereof. Secured around the leg portions 1 are the water bags 5 having an inlet opening closed by the cork 6 and an outlet opening closed by the cork 7.

40 These bags 5 are adapted to be filled with water to keep the body in a vertical position when the life preserver is in use. Secured on the interior of the chest portion of the body A are a plurality of metal reinforcing 45 strips 8 to the top one of which are secured suspending straps 9 which are adapted to go over the shoulder of the wearer.

Secured to the top of the body portion A 50 is a metal band 10 having the flange 11 through which rivets pass engaging the fabric of the body portion for securing the band thereto. The outer surface of the band 10 is threaded. A rubber gasket 12 is received around the band 10 to form a tight fit when 55 the head section is in position.

The head section B has a window 13

formed therein and an air inlet tube 14 extending from the top thereof.

Secured to the bottom edge of the head section B is a metal band 15 which is bent to form a flange 16 by means of which it is attached to the head section, the flanged extension 17 which is interiorly threaded and the shoulders 18 between which is received a ring 19. A hinge 20 is secured to the body portion and to the ring 19 for hingedly connecting the head section with the body section. A plurality of pins or projections 21 are secured on the threaded extension 17 of the band 15 for turning the head section for 70 engaging the threads on the extension 17 with the threaded band 10 of the body section.

Secured to the head section is a signal horn 22 and a signal light 23, each of which 75 may be operated in any manner and which forms no part of my invention. Secured within the body portion, as shown in dotted lines, Fig. 1, is a pocket 24 in which might be placed food or other articles.

Having fully described the detail construction of the invention it is thought that the operation will be clear. When not in use the preserver may be folded into a small space but when it is desired to use the same the head section B is swung upon the hinge 20 so that the person may enter the body portion, the feet entering the portions 2 of the body portion and the arms and fingers entering the portions 3 and 4. The head section is then swung into position over the head and by engaging the pins or projections 21 the head section, which is loosely mounted within the ring 19; may be turned so that the threaded extension 17 90 engages the threaded band 10 of the body portion and the body portion and head portion are thereby held in locked position, the rubber gasket 12 forming a water tight joint. Before entering the water the stopper 6 in 100 the water bag 5 is removed and water allowed to enter the bag. When the bags are filled the stopper is again inserted and when the person is in the water the bags will so weight the preserver as to hold it in a vertical position. The metal reinforcing strips 8 are of particular advantage not only for holding the upper portion of the preserver in position but to prevent pressure against the body by the water. The strips also 105 form the additional purpose of attaching the suspending straps.

In the daytime a signal might be given by means of the horn 22 and at night the light 23 might be used.

Having fully described my invention what I claim as new and desire to secure by Letters Patent is:

1. A life preserver comprising a body section having reinforcing strips secured thereto, straps secured to the said strips, a ring 10 hingedly connected to the body portion, and a head portion loosely mounted in the ring portion and adapted for vertical movement whereby it is secured to the body portion.
2. A life preserver comprising a body 15 portion having a threaded band at the top thereof, a head section having a threaded portion adapted to engage the threaded band of the body portion, a ring carried by the threaded portion of the head section, and a hinge connecting the ring and body portion.
3. A life preserver comprising a body 20 portion having a threaded band secured thereto, a head section having a threaded portion secured thereto, said threaded portion bent to form two shoulders, a ring received on said threaded portion between the shoulders, and a hinge connecting the ring and body portion.
4. A life preserver comprising a body 25 portion having reinforcing bands secured thereto, straps secured to the reinforcing bands, water bags secured to the body portion, a ring connected to the body portion, and a head section loosely mounted in the

ring and adapted for engagement with the 30 body portion.

5. A life preserver comprising a body portion, a ring hingedly secured to the body portion, and a head portion loosely mounted in the ring and adapted to engage with the 40 body portion.

6. A life preserver comprising a body portion, a ring hingedly connected to the body portion, and a head portion loosely mounted in the ring portion and adapted 45 for vertical movement whereby it is secured to the body portion.

7. A life preserver comprising a body portion having a threaded band secured to the top thereof, a ring secured to the body 50 portion, and a head portion having a threaded extension received within the ring for engagement with the body portion.

8. A life preserver comprising a body portion, a threaded band secured to the top 55 of the body portion, a head portion having a threaded extension having a groove therein, and a ring secured to the body portion and received in the groove of the extension of the head portion, said ring being of less 60 width than the groove.

In testimony whereof I affix my signature in presence of two witnesses.

JOSEPH E. LOMAS.
